UNITED STATES PATENT OFFICE.

THOMAS I. RANKIN, OF PHILADELPHIA, PENNSYLVANIA, ASSIGNOR TO THE
ABRAM COX STOVE COMPANY, OF SAME PLACE.

DESIGN FOR A HEATING-STOVE.

SPECIFICATION forming part of Design No. 21,393, dated March 8, 1892.

Application filed February 5, 1892. Serial No. 420,473. Term of patent 7 years.

To all whom it may concern:

Be it known that I, THOMAS I. RANKIN, a citizen of the United States, and a resident of Philadelphia, Pennsylvania, have invented a 5 Design for a Stove, of which the following is a specification.

My design for a heating-stove is fully illustrated in the accompanying perspective view of the stove, the main features of the design 10 being the ornamentation around the fire-door and the ornamentation around the ash-pit door and base.

A is the cylinder of the stove, in which is the fire-door B, having cross-bars b, on which 15 are raised ribs, and at the junction of each cross-bar is a raised knob. The door-frame has raised foliated ornamentation, two foliated scrolls h, extending from the pendant i above the doorway, and on each side of the 20 lower portion of the door-frame are foliated scrolls m, directly above which are rosettes n, one on each side of the frame, and under the doorway is a rosette p, from which extends foliated scrolls s.

25 The cleaner-opening door is represented at c, and d is the ash-pit door. Directly above the cleaner-opening door is a foliated scroll t, and between this scroll and the door is a triangular ornament v on a pebbled background. 30 The outer edge of the door is studded with a single line of circular projections, and the door has an oblong raised panel w with foliated scrolls extending from the edge of the panel toward the center.

35 The ash-pit door has a series of scrolls x overlapping each other at the base and a series of rosettes y situated between the draft-openings.

Below the plain upper band of the base of the stove is an ornamental band, the center 40 figure of which is a shield k, on each side of which are panels k', having a central depending ornamental figure, and beyond the panels are foliated scrolls k².

The foot-rests e e at each side of the stove 45 have rounded ends and have a series of raised rounded ribs on their upper surface.

The top D of the stove has a plain band f, and below this band is a band g of raised 50 rounded ribs. Above the plain band f are ornamental bands g' g² in keeping with the general design of the stove.

I claim—

1. A design for a heating-stove, as fully described, and illustrated in the accompanying 55 drawing.

2. In a design for a heating-stove, the design for the fire-door and frame, substantially as described and shown.

3. In a design for a heating-stove, the 60 design for the cleaner-door and frame, substantially as described and shown.

4. In a design for a heating-stove, the 65 design for the ash-pit door, substantially as described and shown.

5. In a design for a heating-stove, the design for the base-rim, substantially as described and shown.

In testimony whereof I have signed my 70 name to this specification in the presence of two subscribing witnesses.

THOMAS I. RANKIN.
